UNITED STATES PATENT OFFICE.

JAMES BOWES, OF WATERVILLE, NEW YORK.

GAS-GENERATOR.

SPECIFICATION forming part of Letters Patent No. 316,520, dated April 28, 1885.

Application filed November 10, 1884. (No model.)

To all whom it may concern:

Be it known that I, JAMES BOWES, of the village of Waterville, in Oneida county and State of New York, have invented a new and 5 useful Improvement in Gas-Generators; and I do hereby declare the following to be a full, clear, and exact description of the same, reference being had to the accompanying drawings, and to the letters and figures marked 10 thereon.

My invention relates to an improvement in "gas-generators," and embraces the mechanism hereinafter described and claimed.

In the accompanying drawings, Figure 1 is 15 a vertical section view of the generator, incandescent fuel-chamber, grate, and ash-pit, taken through lines *m n* of Fig. 2. Fig. 2 is a section view taken at lines *x y*, Fig. 1. Fig. 3 is a sectional and side view of the oil-jet 20 tube, with a section of the outer sheath removed, exposing the oil-jet tube. Fig. 4 is an end view of the oil-jet tube. Fig. 5 is a side view of the same. Fig. 6 is a section view of the bushing and nut. Fig. 7 is a 25 plan view of the nut.

I will now proceed to describe my invention by reference to the letters marked on the accompanying drawings, in which similar letters refer to corresponding parts throughout 30 the several views.

A represents the outer wall of the generator.

B represents the ash-pit.

C represents the combustion-chamber.

35 D represents the fuel-hopper.

E E E represent projecting protectors over the oil-jet tube and outer tubular sheath, to protect it from the fuel.

F represents the outer tubular sheath 40 inserted in the wall of the generator at four equidistant points at or near the base of the protector, for the reception of the oil-jet tube. It is removable and adjustable from the outside of the generator by means of screw-45 threads G thereon and corresponding threads in the outer wall of the generator.

F' represents the removable oil-jet tube, through which the oil passes into the outer tubular sheath and thence into the fuel-chamber 50 of the generator. This oil-jet tube is provided with screw-threads H thereon, and is

held in a central position within the outer tubular sheath by means of bushing and nut with corresponding threads, H', which render it removable and adjustable from the outside of 55 the walls of the generator.

F² represents the bushing.

F³ represents the nut, with screw-threads H' on the inside thereof, by means of which and the corresponding threads, H, on the oil-jet 60 tube such tube can be adjusted or removed from the outside of the generator, as the operator desires.

It is obvious that other mechanical devices can be substituted for adjusting the outer tubular sheath and the oil-jet tube, and the number of projecting protectors and corresponding sheaths, tubes, bushings, and nuts can be increased or diminished without interfering with the usefulness of my invention. 70

I am aware that an oil-supply pipe fitting in a sleeve so that the oil-pipe may be projected beyond the furnace-wall internally when oil is supplied, and withdrawn when the supply of oil is shut off, has been used. I am also 75 aware that an oil-pipe projecting into the generator surrounding a steam-pipe has been heretofore provided and used. I do not claim either of these devices. So far as I am aware 80 no sheath or sleeve has been provided for protecting the oil-pipe in the manner described herein.

By the use of my protectors a space is maintained between the fuel and oil-jet. My improved oil-jet tube is not subjected to such 85 heat, and the outer sheath protects the oil-jet tube from injury and enables a smaller opening to be used in the oil-jet tube, thereby securing a greater force to the flow of the oil and permitting it to enter nearer the center 90 of the generator than in those heretofore used.

The tube can be easily removed, when desired, in my improved gas-generator, while those now in use are arranged so as to make it difficult to remove the tubes therein. The 95 accompanying drawings show four oil-jet tubes and corresponding protectors; but these can be increased or diminished without interfering with the usefulness of my invention.

What I claim as new, and desire to secure 100 by Letters Patent, is—

The projections E E E, constructed and ar-

ranged as described, in combination with tubular sheath F, held in the wall of the generator at the base of the projections, and an oil-jet tube inserted and held therein by screw-
5 threads and nuts, constructed and arranged substantially as described, for the purposes stated.

Dated and signed at Utica, New York, this
18th day of October, 1884.

JAMES BOWES.
